METHOD OF BLOCK PRINTING SURFACE COVERINGS

Harry S. Humphreys, Lancaster, Pa., assignor to
 Armstrong Cork Company, Lancaster, Pa., a
 corporation of Pennsylvania

Application December 6, 1949, Serial No. 131,300

7 Claims. (Cl. 101—211)

1

This invention relates to a method of block-printing surface coverings in simulation of spatter designs. Early colonial homes, particularly in New England, were frequently provided with decorative floors obtained by coating the floor boards with paint of a base color and spattering the base color with one or a number of differently colored paints. The spatter colors were applied by dipping a brush into the paint to be spattered and tapping the brush on a small piece of wood to project drops of the paint onto the base coat. The drops spattered upon falling onto the base and were of irregular size and shape. In some instances, the background was of a multicolor, obtained by applying a base color paint, permitting it to dry, and then applying a graining paint thereover and brushing or combing the over-applied paint to obtain a multicolored background. The spatter colors were then applied over the grained background paint subsequent to drying. In the spattering of the paints over the background, a random arrangement of the spatter colors was obtained, with some of the spattered areas lying in contiguous relationship to one another and others being spaced apart. In addition, as mentioned above, the spattered areas varied in size from areas almost imperceptible to the eye from the average height of a person walking on the floor to areas much larger. The spatter colors were characterized by their irregularity of shape and size.

In my copending application, Serial No. 100,167, filed June 20, 1949, and entitled "Surface Covering and Method of Making the Same," there is disclosed a surface covering of the inlaid linoleum type in simulation of a spatter decorated floor. In the production of the cheaper hard surface floor coverings by the application of paint to a supporting backing such as waterproof felt, most common practice is to employ flat block-printing machines in which the printing surfaces are of substantially regular geometrical outline. Such printing blocks apply a heavy layer of relatively thick paint onto the supporting layer. Due to the regular geometrical outline of the printing surface, it is not possible, following conventional practice, to secure intricate fine line designs; and the production of a product in simulation of a spatter decorated floor could not be successfully obtained following conventional practice in block-printing of surface coverings.

The primary object of the present invention is to provide a method of block-printing surface coverings in simulation of spatter designs having the irregularly disposed and shaped spatter-re-

2

resenting colors, with the characterizing nongeometrical outlines.

Other objects of the invention will be apparent from a consideration of the detailed description of certain preferred embodiments of the invention which follow.

Generally, in the practice of the method of this invention, the spatter-representing paints in a plurality of colors are printed onto the supporting foundation of waterproof felt or the like with flat printing blocks having printing surfaces of substantially regular geometrical outline. The spatter colors are of many different sizes and are disposed in random arrangement on the foundation layer. Background colored paint is printed with similar printing surfaces onto the supporting web, with the wet spatter and the background paints irregularly overlying one another at their zones of juncture and providing irregular edges of substantially nongeometrical outline on the randomly arranged spatter-representing areas. The spatter colors are preferably applied to the foundation first and the background color or colors applied subsequently, with the background and spatter paints overlapping at the zones of juncture. The background paint may be applied first, however, and the spatter color paints applied thereover with overlapping juncture lines, or one or more of the spatter-color paints may be applied prior to the background paint and another or others afterwards. In order to enhance the natural spatter effect, some of the spatter colors should lie in contiguous relationship to one another and in overlapping relationship at their zones of juncture and others should be separated from adjacent spatter colors by the background paint.

Certain preferred embodiments of the invention are illustrated in the attached drawings in which:

Figures 1A and 1B are diagrammatic views illustrating a series of printing steps in the practice of the process;

Figure 2 is a top plan view of a small portion of a flat printing block illustrating a portion cut in design and a portion uncut;

Figure 3 is a diagrammatic view of a flat block-printing machine; and

Figures 4 and 5 are diagrammatic plan views of block-printed surface coverings in simulation of spatter designs produced by two modifications of the invention.

Referring first to Figure 3, there is shown diagrammatically a flat block-printing machine including a bed 2 over which a supporting founda-

tion 3 of waterproof felt or the like is intermittently fed from a roll 4. The machine is provided with printing blocks 5 to 11 which are spaced apart a distance equivalent to the width of the printing surfaces of the blocks so that upon a uniform intermittent movement of the foundation layer 3 corresponding to the width of the printing surface, the printed areas will be sequentially brought into proper registry under the printing blocks. The printed material is shown as being delivered from the printing machine to a stove or other drying chamber where the paint applied by the printing blocks is dried.

Referring to Figures 1A and 1B which show a very small portion of surface covering—commercial practice is to produce such coverings in widths from 6 feet to 12 feet and of indefinite length—spatter-color paint which has been shown as a yellow color is applied by the printing block 5. It will be observed that the yellow-colored spatter areas 12 are of substantially regular geometrical outline, although there has been some flow of the heavy paint on the foundation layer 3. The regular geometrical outline of the printed areas 12 results from the use of a sawn-type flat printing block. While these blocks are conventional in the floor covering industry, a portion of one has been shown in Figure 2. The major portion of this block has been shown as cut, ready for printing, but a small portion in the lower right-hand corner has been shown as supplied to the block cutter for preparation of the printing surface. The block is formed of laminated wood and has a printing surface 13 which is provided with spaced upstanding printing surfaces 14 extending longitudinally of the printing block and formed by sawing grooves in the surface of the wood block. The portions 14 may be spaced ten to the inch. The desired design is laid out on the surface of the block as illustrated by the fine lines in the lower right-hand portion of Figure 2, and workmen then cut away portions of the upstanding ribs 14, leaving upstanding the printing portions 15 which are to apply paint. This cutting is done manually with chisels and with powered routers. It will be observed that the printing surfaces 15 are of regular geometrical outline. A substantially heavy-bodied paint is employed in the floor covering industry; and when applied to the printing surface 15 with the conventional paint trough and roller arrangement and the printing surface brought into engagement with the foundation to be printed, the applied paint 12 has a substantially regular geometrical shape or outline as noted in Figure 1A.

Referring again to Figures 1A, 1B, and 3, the foundation material 3 with the applied yellow spatter areas 12 is moved to bring the portion printed by the block 5 into registry with the block 6 which applies red spatter-color paint onto the backing in the areas 16. It will be observed that some of the red spatters 16 are in contiguous relationship to yellow spatters 12. The operation is repeated and block 7 applies blue-colored paint in spatters 17, block 8 applies green-colored spatters 18, block 9 black spatters 19, and block 10 grey spatters 20. Light lines have been shown between the various sections in Figures 1A and 1B, but these, of course, would not appear in the printed product.

Block 11 applies a background color. The block 11 is so cut that its printing surface overlaps, slightly at least, the spatter-color areas. A heavy-bodied paint is used as the background paint, and when it is applied there is an irregular

intermingling of the background and spatter paints at the zones of juncture between the background and the spatter colors where they overlap. The background color being applied over the spatter colors tends to flow slightly thereover to produce generally convex lines of juncture as indicated at 22, and this results in the provision of correspondingly concave lines on the spatters which give them relatively sharp points as indicated at 23. This heightens the effect, for when paints are spattered, many of the spattered areas have sharp but fine projecting portions. When the product is viewed from eye level by a person standing on the floor, the effect is a close simulation of a spatter design floor made by spattering paints on a background color. The random arrangement, the difference in size, and the irregular shape of the spatters all contribute to the attainment of the desired effect.

While it is preferred to have the spatter colors applied first, some or all of them may be applied over the background color. When this practice is followed, the block for printing the background color will be cut so as to leave open, uncovered areas on the foundation, into which the spatter colors may be inserted by subsequent printing blocks. These spatter colors will be printed so as to overlie the background color at the zones of juncture to provide the irregular juncture lines. This will not produce the sharp projecting points which appear in the product produced in accordance with the preferred practice. The product produced by this modified procedure is shown in Figure 4 where the spatter colors 24 are applied over the background color 25.

A further modification of the method may be employed to produce a product such as shown in Figure 5. In this case, the spatter colors 26 were applied first and the background colors 27 and 28 were applied thereover in a manner to simulate the multicolored background referred to above, and additional spatter colors 29 were applied after the background colors. This produces a unique effect in that some of the spatter areas have sharp points, such as the areas 26, and others 29 are irregularly shaped but not pointed. In spattering, some of the spatters will naturally have an irregular shape without pointed projections, while others will have such projections. This effect is obtained by printing the background paint after some of the spatter paints have been applied, and applying one or more spatter-color paints after the background paint has been applied.

Each of the colors is applied while the others are wet; and as a result the colors tend to level and upon stoving provide a smooth, hard surface covering which will maintain its design throughout the entire thickness of the wear layer.

By this invention, it is possible to produce on conventional flat block-printing machines surface coverings in simulation of spatter designs with the usual heavy-bodied printing paints which provide an adequate wearing surface for floor covering and other uses.

I claim:

1. In a method of block-printing surface coverings in simulation of spatter designs with flat printing blocks having printing surfaces of substantially regular geometrical outline, the steps comprising printing upon a supporting web spatter-color-representing paint of one color in random arrangement with a flat printing block 75 having printing surfaces of substantially regu-

lar geometrical outline, printing upon said web with a similar printing surface spatter-color-representing paint of another color with some only of said second printed portions overlapping the edges of some only of said first printed portions to provide a plurality of spatter-color-representing areas of each color disposed in spaced relationship on the backing and other spatter-color-representing areas in edge-overlapping relationship on the backing, and printing background paint with similar printing surfaces upon said web with the wet spatter-color representing and background paints irregularly overlying one another at their zones of juncture and providing irregular edges of substantially non-geometrical outline on substantially all of the randomly arranged spatter-color-representing areas.

2. In a method of block-printing surface coverings in simulation of spatter designs with flat printing blocks having printing surfaces of substantially regular geometrical outline, the steps comprising printing background paint upon a supporting web with printing surfaces of substantially regular geometrical outline to provide a layer of paint on the web provided with spaced unprinted areas extending from the upper surface of the printed layer toward the supporting web disposed in random arrangement, and while the background paint is wet, printing a spatter-color-representing paint of one color with similar printing surfaces onto the supporting web in a portion of said unprinted areas, printing upon said web in another portion of said unprinted areas with a similar printing surface spatter-color-representing paint of another color with some only of said second printed portions overlapping the edges of some only of said first printed portions to provide a plurality of spatter-color-representing areas of each color disposed in spaced relationship on the backing and other spatter-color-representing areas in edge-overlapping relationship on the backing, with the spatter-color-representing paints irregularly overlying the background paints at the zones of juncture between the two and providing irregular edges of substantially nongeometrical outline on substantially all of the randomly arranged spatter-representing areas.

3. In a method of block-printing surface coverings in simulation of spatter designs with flat printing blocks having printing surfaces of substantially regular geometrical outline, the steps comprising printing a spatter-color-representing paint of one color in random arrangement upon spaced areas of a supporting web with flat printing blocks having printing surfaces of substantially regular geometrical outline, printing upon said web with a similar printing surface spatter-color-representing paint of another color with some only of said second printed portions overlapping the edges of some only of said first printed portions to provide a plurality of spatter-color-representing areas of each color disposed in spaced relationship on the backing and other spatter-color-representing areas in edge-overlapping relationship on the backing, and, while the spatter-color-representing paints are wet, printing background paint with similar printing surfaces onto the supporting web in the unprinted areas and over the marginal edges of the spatter-color-representing paints, with the overlying edges of the background paint in a substantial portion at least thereof being of generally irregular convex

shape to provide generally concave serrated edges on a substantial portion at least of the spatter-color areas.

4. In a method of block-printing surface coverings in simulation of spatter designs with flat printing blocks having printing surfaces of substantially regular geometrical outline, the steps comprising printing upon a supporting web spatter-color-representing paint of one color in random arrangement with a flat printing block having printing surfaces of substantially regular geometrical outline, printing upon said web with a similar printing surface spatter-color-representing paint of another color with some only of said second printed portions overlapping the edges of some only of said first printed portions to provide a plurality of spatter-color-representing areas of each color disposed in spaced relationship on the backing and other spatter-color-representing areas in edge-overlapping relationship on the backing, printing background paint with similar printing surfaces onto the supporting web with spaced unprinted areas extending from the upper surface of the printed layer toward the supporting web disposed in random arrangement, and printing spatter-color-representing paints of additional colors with similar printing surfaces onto the supporting web in said unprinted areas with the wet spatter-color-representing paints last applied overlying the wet background paint and with the wet background paint overlying the wet spatter-color-representing paints first applied at the zones of juncture between the background paint and the spatter-color-representing paints to provide irregular edges of substantially nongeometrical outline on substantially all of the randomly arranged spatter-representing areas.

5. In a method of block-printing surface coverings in simulation of spatter designs with flat printing blocks having printing surfaces of substantially regular geometrical outline, the steps comprising printing upon a supporting web spatter-color-representing paint of one color in random arrangement, printing upon said web spatter-color-representing paint of another color with some only of said second printed portions lying in contiguous relationship with some only of said first printed portions and with others in spaced relationship, said paints being applied with flat printing blocks having printing surfaces of substantially regular geometrical outline, and printing background paint with similar printing surfaces onto the supporting web, with the wet spatter and background paints irregularly overlying one another at their zones of juncture and providing irregular edges of substantially nongeometrical outline on substantially all of the randomly arranged spatter-representing areas.

6. In a method of block-printing surface coverings in simulation of spatter designs with flat printing blocks having printing surfaces of substantially regular geometrical outline, the steps comprising printing upon a supporting web spatter-color-representing paints in a plurality of colors in random arrangement with some of the areas of the spatter-color-representing paint being larger than others and with some only of the wet spatter-color paints irregularly overlying one another at their zones of juncture only, to provide a plurality of spatter-color-representing areas of each color disposed in spaced relationship on the backing and other spatter-color-representing areas in edge-overlapping re-

relationship on the backing, and printing background paint with similar printing surfaces onto the supporting web with the wet spatter-color and the wet background paints irregularly overlying one another at their zones of juncture and providing irregularly shaped edges of substantially nongeometrical outline on substantially all of the randomly arranged spatter-representing areas.

7. In a method of block-printing surface coverings in simulation of spatter designs with flat printing blocks having printing surfaces of substantially regular geometrical outline, the steps comprising printing upon a supporting web spatter-color-representing paint of one color in random arrangement with flat blocks having printing surfaces of substantially regular geometrical outline, while said paint is wet printing upon said web with a similar printing surface spatter-color-representing paint of another color with some only of said second printed portions overlapping the edges of some only of said first printed portions to provide a plurality of spatter-color-representing areas of each color disposed

in spaced relationship on the backing and other spatter-color-representing areas in edge-overlapping relationship on the backing, and printing a multicolored background with similar printing surfaces onto the supporting web while the spatter-color-representing paints are wet, the said spatter-color and background paints irregularly overlying one another at their zones of juncture and providing irregular edges of substantially all of the randomly arranged spatter-representing areas.
